John Cooper & Andrew Doty, of Morehough,
State of Pennsylvania

Letters' Patent

The schedule referred to in these Letters' Patent as making part of the same, containing a description in the words of the said John Cooper & Andrew Doty, themselves of their improvement in the Machine for Hauling Coal or

It is known that the John Cooper and Andrew Doty of Morehough in the County of Columbian and State of Pennsylvania have invented an improvement in the "Coal Hauler" viz This Machine consists of a cast iron cylinder furnished with triangular teeth, a cast iron concave also furnished with triangular teeth, a wooden shaft, through the cylinder with a wheel on one end of the shaft, keelsons, and tail boards, all of which are placed in a wooden or plank frame, consisting of two parts (an upper and lower) which separate horizontally about the centre, The cylinder is hollow about eighteen inches in diameter, and may be made thirty inches in length, more or less, to suit the power to be applied or the inclination of the owner. It is composed of two cast iron heads, forming the ends and of six staves, the staves are put together by setting the ends thereof into a groove, and in the rim of each head about three fourths of an inch from the out edge thereof, and when the staves and heads are thus fitted together, they are fastened together by six wrought iron rods passing through the heads, immediately within the circle of the staves; each rod having a head on one end, and a screw and bear on the other end, by which they are to be firmly drawn together. The concave surface of the cylinder is to be flattened longitudinally, and the outer edges of the heads are to be notched so as to correspond.

with the fluting of the cylinder. The head consists of a rim about two inches wide, of iron, and a circular piece in the center, of two or more inches radius, through which a square hole is left to admit a shaft of suitable thickness for the cylinder to revolve on and immediately within the groove above mentioned, and when the arms unite with the rim, six circular holes are to be made for the rods to pass through by which the several parts of the cylinder are to be fastened together, each head with all its arms, pins, grooves and the notches round the edge is to be moulded and cast complete. The thickness of the cast iron, in the heads and stems, is to be about an half inch.

Each stem of the cylinder is to be curved to a radius suited to the intended diameter, and to be wide enough to form one sixth part of a circle exclusive of the top at each edge; and is to be furnished with triangular teeth set in rows at a proper distance from each edge, in a transverse order so that the several teeth forming a longitudinal row shall not meet in a cavitation, work, precisely, between the teeth made out by the teeth of the adjacent row. The number of teeth must be even, to suit the length of the cylinder, and for closing. Clover head, for which this is principally intended, the teeth of the cylinder and of the concave should work within about a quarter of an inch of each other, and the teeth of one should work within about a quarter of an inch of the surface of the other. The teeth of the cylinder are to be sloped back, and notched on the front, from the back, to the vertical angle, and they are to be three fourths of an inch high. The notched rims of the heads cylinder and three fourths of an inch above the surface of the cylinder are each intended to answer the purpose, of a ring of teeth, — The concave consists of two cast iron stems, half an inch thick, made to correspond with the cylinder in curvature, the radius thereof being one inch larger than that of the cylinder. The teeth are to

be triangular and of the same length as height above the surface with those of the cylinders. — Two rows of these are to be set in regular order along each stave on the concave side. The surface of the concave is also to be fluted longitudinally. The staves of the concave are to be fixed with their ends into grooves, to be cut in the end planks of the frame, at a proper distance from the centre of motion of the cylinders, one stave in the lower part of the frame, and the other in the upper part so that when the two parts are put together, the two staves shall come in contact and form together, a segment of about one third of a circle round the cylinder — one half being above, and the other half below, the centre of the cylinder —

The screen is to consist of iron wire, or, perforated sheet iron, and is to be fixed into the frame in a manner similar to that described for fixing the concave, about two thirds thereof is to be fixed into the lower part of the frame, forming with the lower staves of the concave, a continuous curve, of equal radius with the surface of the concave, and making with the lower half thereof a complete semicircle. The remaining part of the screen is to be fixed in the upper part of the frame, so that when put together it will continue the curve up to a horizontal line with the top of the upper staves of the concave — the radius of the curve formed by the upper part of the screen, gradually increasing from the bottom upwards, so that the upper edge of the screen may have receded about an inch further from the centre than the lower edge is, in order to give more room between the screen and the cylinder at that place.

The higher boards are to be fixed also to the end planks of the upper part of the frame and attached to the upper edge of the concave, at one side, and to the upper edge of the screen at the other side and to be so placed as to form a kind of shield, to conduct one and confine whatever is thrown into it to the action of the revolving cylinder.

The tail boards are to be placed below the screen that every thing which passes through the screen may be conducted by them through the opening between them, to the "converging fan," to be placed beneath the machine. The frame is composed of timber or plank. The end of the lower part upon which the cylinder stands, should be four
tire and a half to three inches thick, every other part may be made thinner, the parts of the frame are so constructed that they may separate horizontally at the centre of the shaft; the upper part carrying with it when taken off, the upper part of the concave, the upper part of the screen, and the upper boards, and leaving all the cylinders, from the centre upwards, exposed to view and free to be removed at pleasure. The upper and lower parts of the frame are kept in their proper places, in relation to each other, by dovetails. The position of the cylinders when the machine is put together is horizontal, and it is nearly enclosed in the inverted cone formed by the concave and the screen. The motion of the cylinders must be so directed, that its
left and convex surface will pass the "concave," downward and never in a contrary direction. The cylinders are to be put in motion by means of a wheel and a whip properly attached to one end of the shaft.

Explanation of the Drawings.

Fig. 1st represents the head of the cylinder of which A is the
groat B, the square hole in which to mount the shaft C.C.C.C.C.C.
the big circular hole through which to pass the rods used for
fastening and holding the several parts of the cylinder together
D.D.D.D.D. the six comers. Two such heads are required for the
cylinder. The outer edge of the rim (E) is notched to answer
the purpose of a ring of teeth. Fig. 2nd represents a transverse
section of the cylinder when put together, and cut through a
ring of teeth in which a, a, a, a, a, a, are the six stars showing
the top of the edges and the planing of the surface. b, b, b, b, b,
are a ring of teeth shaped back and notched in the front from

the base to the vertical angle; they are thick forth of an inch in length from the surface of the cylinder to the vertical angle or point c.c.c.c., are the top iron pins used for fastening and holding the several parts of the cylinder together and are immediately within the ring or circle formed by the staves. d, the square shaft in the center - The part (e), shows what direction ought to be given to the mallet to suit the cut and shape of the teeth they being notched on the front. Fig. 3. Represents a cross section of the concave composed of the staves cut through a transverse row of teeth showing the shape of the teeth as at d, and the fluting of the concave surface as at 7.7.7. 7.7.

Fig. 4. Represents a transverse section of a single stave of the cylinder. Fig. 5. Is a concave view of a single stave of the cylinder showing the manner of distributing or placing the teeth upon it which are represented at a.a.a.a.a.a. Fig. 6. Is a concave view of one stave of the concave showing the manner of distributing the - upon it. The teeth appear in two regular rows, as at a.b.a.b.a.b. &c. Fig. 7. Is a top view of the cylinder placed in the lower part of the frame, exhibiting the situation of the teeth on the cylinder, as at a.a.a.a.a.a. 7.7. and the upper edge of the lower staves of the concave at b) with the upper row of teeth at c.c.c. 7.7. and on the opposite side of the cylinder, the upper edge of the lower part of the concave &c. &c. are the end-boards of the frame into which the ends of the concave are let at f.f. and into which the ends of the scones are let at g.g. - h.h.h.h. are mortises for the doors which are fast to the upper part of the frame - i. the wheel and k. k. the quadrants upon which the cylinder turns.

Fig. 8. Represents a transverse section of the frame including the concave, screen, hopper, boards, and tail boards. the cylinder being cut at. a. are the end boards of the upper part of the frame 13. 13. the upper and lower staves of the concave C, C, the upper and lower parts of the scones - D.D.D.

the hopper being to be, the tail boards, & the opening through which every thing passes through the screw is attached to the aforesaid fan beneath the machine and by a hole in the end for a judgment of the shaft to work in. When the cylinder is placed in as at fig. 7th, and the upper part of the frame is put on, as at fig 8th, the machine is prepared for use.

Method of using the mill or machine. When the machine is prepared as above described it is then coupled to the hulling of Clovers seed only a quick working motion being communicated to the cylinder by means of a strap and wheel as aforesaid the hopper is to be filled with the chaff containing the seed, which must then be permitted to remain until it becomes fine enough to pass, (chaff and all) through the screw, and so draw through the opening between the tail boards to the fan. The operation is attended with no further trouble than that of keeping the hopper filled, and the process of hulling will be safely performed by the operation of the machine. In order to adapt it to the hulling or threshing of other seed, or grain, the upper part of concave and the whole of the screw must be removed.

What we claim as our invention is the manner of connecting the cylinder, (as we are aware the cylinder, have been long in use, but not constructed after the manner of ours) We therefore claim the method of fitting the circumference, and the outer edge or periphery of the head.

Secondly, the manner of securing the staves and heads together by means of the wrought iron, works as described.

Lastly, the manner of connecting the slotted and notched teeth with the flat side cylinder as set forth above.

In testimony that the above is a full and accurate description of our improvement as invented by us we have hereunto set our hands,

Walter D. Davis Petorini

John Sholes
